CLAIM

We claim the ornamental design for a display fixture, as shown and described.

DESCRIPTION

FIG. 1 is a perspective view of a display fixture;

FIG. 2 is a front view thereof;

FIG. 3 is a side view thereof, the opposite side being a mirror image;

FIG. 4 is a top view thereof; and,

FIG. 5 is a bottom view thereof.

The broken lines shown illustrate portions of the display fixture which form no part of the claimed design.
